[57] CLAIM

The ornamental design for a peg and ring game, as shown and described.

DESCRIPTION

FIG. 1 is a perspective view of a peg and ring game showing our new design;

FIG. 2 is a top plan view thereof;

FIG. 3 is a left side elevational view thereof; the right side elevational view being a mirror image thereof;

FIG. 4 is a front elevational view thereof; and,

FIG. 5 is a bottom plan view thereof.

The broken line showing of a board surface in FIG. 1 is for illustrative purposes only and forms no part of the claim.
